TOBACCO STEMMING AND THRESHING
MACHINEJames P. Durning, St. Albans, N. Y., assignor to
International Cigar Machinery Company, a
corporation of New Jersey

Application October 3, 1935, Serial No. 43,330

64 Claims. (Cl. 131—57)

This invention relates to tobacco stemming and disintegrating or threshing machines, more particularly to a machine for disintegrating leaf tobacco and winnowing the same to provide short filler suitable for the manufacture of scrap cigars. The main object of the invention is to break up the tobacco leaves and to thoroughly remove the stem portions which are not suitable for use with the laminae as short filler. To this end an improved winnowing device is provided for the pneumatic separation of the laminae, the stem portions having adhering laminae and the stem portions substantially devoid of laminae, the different specific gravities of the same being utilized to effect the desired segregation.

A further object of the invention is to winnow the disintegrated leaves with separate currents of air whereby most of the laminae are removed therefrom in the first air current and the remainder is re-subjected to the second air current for further removal of any remaining laminae, and separation of any stem portions having adhering laminae. Still another object of the invention is to return the stem portions having adhering laminae, after the same have been segregated, to the disintegrating means for further removal of laminae therefrom. To these ends the winnowing device comprises a tower having an inlet and outlet, the inlet being subdivided into primary and secondary feed channels communicating with the tower outlet and return channels communicating with said feed channels, and a blower delivering a divided blast for creating separate air currents through the primary and secondary channels, wherefore the laminae will be winnowed from the disintegrated leaves introduced into the primary channel and carried into the tower outlet and the stem portions will be carried over into the return channels to be conducted into the current of air entering the secondary channel whereby the laminae carried over with stem portions will be propelled into the tower outlet and the stem portions having adhering laminae will pass through a pocket in one of the walls of the secondary channel and will be returned to the disintegrating means by conveyor belt. The laminae and stem portions having adhering laminae are separated in this manner from the stem portions devoid of laminae.

A further important object of the invention is to remove dust and sand from the disintegrated leaves, and for this purpose the disintegrated leaves may be transported to the tower inlet on

a screen belt running over a suction intake connected to a suction fan, the belt being suitably agitated to loosen the dust and sand in the disintegrated leaves so that it may be more readily removed by the suction created in said intake. A thresher of the well known Cardwell type may be used for disintegrating the leaves which may be delivered to the thresher by a conveyor belt, and a still further object of the invention is to remove dust and sand from the leaves prior to their delivery to the thresher.

Another important object of the invention is to effect the proper separation of laminae and stem portions having adhering laminae from various grades of disintegrated tobacco, and with this end in view the secondary feed channel and the return channels are provided with gates which may be adjusted to effect the required segregation with the selected grade of tobacco.

The velocity of the separate air currents is adjusted to effect the proper segregation, and the same is accomplished in accordance with an additional object of the invention by providing a blower delivering a divided blast into the primary and secondary feed channels, the nozzle of the blower having separate orifices arranged below the primary and secondary channels. The velocity of the separate currents through the orifices may be governed to effect the required segregation in the primary and secondary channels, by independently adjustable sets of shutters in the orifices or independently adjustable shutters on the inlets of the blower housings.

According to a modified form of the invention the dust and sand may be removed from the disintegrated leaves while they are being winnowed in the tower, the latter for this purpose having a screened perforation covered by a jacket connected to suction. With these and other objects not specifically mentioned in view, the invention consists in certain constructions and combinations hereinafter fully described and then specifically set forth in the claims hereunto appended.

In the accompanying drawings which form a part of this specification and in which like characters of reference indicate the same or like parts:

Fig. 1 is a section side elevation of a stemming and threshing machine, embodying the invention;

Fig. 2 is a partial side elevation of the same, taken on line 2—2 of Fig. 3;

Fig. 3 is an end elevation of the machine as seen from line 3—3 of Fig. 1;

Fig. 4 is a fragmentary view of one of the gates adjustably mounted within the winnowing tower;

Fig. 5 is a detail side elevation of a modified form of winnowing tower wherein the dust and sand are removed from the disintegrated tobacco during the winnowing operation;

Fig. 6 is a sectional side elevation of a suitable form of twin blower delivering a divided blast for creating separate air currents in the winnowing tower, taken on line 6—6 of Fig. 7;

Fig. 7 is a plan view of the same; and

Fig. 8 is a partial side elevation of the blower nozzle illustrating a modified form of control mechanism.

Generally stated, in the particular embodiments of the invention herein illustrated the tobacco leaves are disintegrated and subjected to separate air currents to segregate therefrom the 20 laminae and the stem portions having adhering laminae. The latter are preferably returned to the disintegrating means for further removal of laminae therefrom. In the best constructions contemplated the disintegrated leaves are 25 introduced into the inlet of a winnowing tower which is subdivided into primary and secondary feed channels and return channels communicating with the feed chutes, and subjected to a divided blast which carries 30 the laminae up the primary channel into the tower outlet, the stem portions being carried over through the return channels into the air current entering the secondary channel, for further winnowing of any laminae carried over therewith 35 and segregation of stem portions having adhering laminae. The latter, in the best constructions contemplated, are returned to the disintegrating means for further removal of laminae therefrom. The particular machine selected to 40 illustrate the invention is but one of many possible concrete embodiments of the same. The invention, therefore, is not to be restricted to the details illustrated and described nor to the particular embodiments chosen as illustrative of the invention, as the same may be widely varied in 45 construction.

Referring to the drawings, the improved stemming and threshing machine selected to illustrate the invention consists of a main frame 10 and a separating or winnowing tower 11 attached to the latter. Frame 10 also supports a thresher which may have any suitable or desirable construction but preferably comprising a threshing chamber consisting of a concave 12 and a hinged lid 13. The tobacco leaves L are placed by an attendant on a continuously moving conveyor belt 14 (Fig. 1) and are fed under a pressure roll 15 into the thresher. On the periphery of a drum 16 revolving continuously within the threshing chamber are fastened a number of bars carrying integral threshing spikes 17. The spikes 17, as they revolve with the drum 16, pass between a number of stationary spikes 18 arranged in a row or other desirable formation and attached to the lid 13 of the threshing chamber. The drum 16 is mounted on a shaft 19 supported in bearings of the main frame 10. Shaft 19 carries a pulley 20 (Fig. 3) which may be driven by any suitable means such as V-belts 21, from a pulley 22 mounted on the shaft 23 of a motor 24 supported by a bracket 25 fastened to main frame 10.

The conveyor belt 14 is driven by the pulley 26 and is led over an idler pulley 27 mounted on a shaft 28 mounted in adjustable bearings of sup-

porting brackets 29 attached to main frame 10. The driving pulley 26 is mounted on a shaft 30 also supported in bearings of the brackets 29. Shaft 30 carries a sprocket 31 driven through a chain 32 (Fig. 3) by a sprocket 33 mounted on a cross-shaft 34 supported in bearings of the main frame 10. Shaft 34 is provided with a bevel gear 35 meshing with a bevel gear 36 mounted on a vertical shaft 37 carrying a spiral gear 38 meshing with a spiral gear 39 (Fig. 1) mounted on the drum shaft 19. Spiral gears 38 and 39 are concealed in a gear housing 40 attached to main frame 10. In order to confine the tobacco leaves L on the moving conveyor belt 14 a pair of guides 41 are attached to lugs 42 of brackets 29 at each side of belt 14. The pressure roller 15 is mounted on a shaft 43 supported in floating bearings of brackets 29, and serves to compact the layer of tobacco leaves passing thereunder and prevent removal of unduly large masses of leaves by the successive rows of spikes in their movement past the pulley 26. Shaft 43 carries a shrouded gear 44 (Fig. 2) which is driven by a shrouded gear 45 mounted on the pulley drive shaft 30.

Upon entering the threshing chamber the tobacco leaves L are engaged by the threshing spikes 17 on the revolving drum 16 which act to sweep the leaves against the stationary spikes 18, causing the stems to be torn from the leaves and the latter to be disintegrated. The broken stem portions and laminae then fall to the concave 12 which has interstices or perforations 46 (Fig. 1) of a desired size or shape according to the size of scrap tobacco wanted. It should be noted that the construction just described is of the well known Cardwell type and that other suitable disintegrators may be used instead. Laminae and stem portions of the desired size fall through the holes 46 on to a continuously moving screen belt 47 (Fig. 1) underneath which is mounted a suction intake 48, thereby causing removal of dust and sand D from the disintegrated tobacco leaves while they are transported on the screen belt 47, by suction created by a suction fan 49 located in a housing communicating with the intake 48. The suction fan 49 is provided with a pulley 50 driven through a belt 51 from another pulley 52 mounted on shaft 23 of the motor 24. To the suction intake 48 is furthermore attached a suction conduit 53 connected to a suction chamber 54 forming a part of the stationary threshing chamber casting 13a on which the lid 13 is hinged. The suction chamber 54 is provided with an elongated slot 55 (Fig. 1) through which some of the dust and grit D of the tobacco leaves are removed before the latter enter the threshing chamber. To the front of the suction chamber 54 is attached a plate 56 for the purpose of concentrating the suction upon the leaves just about to be engaged by pressure roller 15. The double dust removing system just described assures removal of all dust, grit and sand from the tobacco before the laminae are winnowed from the stem portions. Furthermore, any desired size of scrap may be obtained by replacing the concave 12 with a concave having interstices or perforations of different diameter.

The screen belt 47 is driven by a pulley 57 mounted on a shaft 58 (Fig. 1) supported in bearings of the main frame 10. Shaft 58 carries a sprocket 59 (Fig. 3) which through a chain 60 is driven by a sprocket 61 mounted on a cross-shaft 34. Screen belt 47 is led over an idler pulley 62 loosely mounted on a stationary shaft 63, and its upper run is agitated by knockers 64 to 75

loosen the dust and sand from the disintegrated tobacco thereon and its lower run is supported by a number of rollers 64a mounted in bearings of main frame 10.

5 The traveling screen belt 47 carries the laminae and the stem portions towards the winnowing tower 11, and, as the laminae and stems fall from the screen belt 47, they are blown upward into the inlet by an air current coming out of one orifice 65 of the nozzle 66 of a twin blower 67 creating a divided air blast. The inlet of the winnowing tower 11 is subdivided by a central transverse partition or wall 68c into generally vertical primary and secondary feed channels, the primary feed channel being further sub-divided by partitions 68a and 68b to form return channels extending upwardly and communicating with the secondary feed channel. The partition 68b has a corrugated configuration and together with the 10 corrugated partition 68 provides a tortuous passage for the disintegrated tobacco while it is being carried up in the primary feed channel by the current of air delivered from the orifice 65 of the blower nozzle, wherefore the stem portions 15 will impinge repeatedly on these partitions until they are carried over into the return channels. It should be noted that the described arrangement of corrugated partitions in the primary channel provides expanded sections adjacent the 20 upper ends of the return channels, thereby diminishing the velocity of the air current through expanded sections and thus permitting the stem portions to be carried over and drop into the return channels by reason of their greater specific 25 gravity. The laminae, however, are carried up the primary channel and over into the tower outlet, whence they fall into a receptacle 69 in which they are collected.

Each of the return channels and the secondary 30 feed channel have gates 70 at their upper ends which can be set at any desirable angle. Each gate 70 is mounted on a shaft 71 supported in bearings provided in the side walls of the tower 11. One end of each shaft protrudes from the 35 tower and is equipped with a knob 72 (Figs. 3 and 4) carrying a pointer sliding over a dial 74 attached to the exterior of one of the tower walls. The pointer 73 thus indicates on the dials 74 the exact position of the individual gates, 40 wherefore the same may be set to effect the required segregation of the laminae, the stem portions having adhering laminae, and the stem portions substantially devoid of laminae.

The laminae blown up the primary channel 45 into the tower outlet are, of course, suitable for use as short filler, but it is desirable to re-subject the stem portions carried over into the return channels to a further winnowing operation to separate therefrom any laminae that may 50 be carried over therewith. Accordingly, as the stem portions, and any laminae and curled tip ends accompanying the same, drop down through the return channels they encounter a second current of air issuing from the second orifice 75 of the nozzle 66. This current of air is too weak 55 to send them back up the return channels and propels the laminae up the secondary feed channel into the tower outlet, whence they likewise fall into the receptacle 69. The spaced baffle- 60 plates 68d and 68e at the entrance of the secondary channel guide this portion of the divided blast delivered by the blower nozzle, into the secondary channel, and the lower ends of the partitions 68a and 68b are provided with streamlined lips opposite the baffle-plates to reduce the 65

resistance to the flow of the air current there-between and prevent the formation of whirl-pools.

Certain of the stem portions dropping into the secondary air current from the return channels namely the excessively large or heavy stem portions substantially devoid of laminae, will fall down along the baffle-plate 68d into the receptacle 76, but the remaining stem portions will be carried up into the secondary channel with 10 the laminae. Some of the stem portions substantially devoid of laminae will impinge on the baffle 68e and drop through the space between the same and the other baffle into the receptacle 15 76. The remaining stem portions will be carried into the secondary channel for segregation therefrom of any curled tip ends and stem portions having adhering laminae.

It should also be noted that the wall 68c forming one side of the secondary channel has a corrugated configuration and the opposite side constitutes the inner wall of a return duct 77. The same is provided with adjustable gates 70a which may be set to form a pocket of any desired width therebetween through which the curled tip ends 20 and stem portions having adhering laminae will pass as they are carried up the secondary channel by the air current therein. These gates 70a are likewise mounted on shafts 71 mounted in the sides of the winnowing tower and each is 25 provided with a pointer 73 riding over a dial 74 (Figs. 3 and 4), wherefore they may be set by the attendant to cause all the stem portions having adhering laminae to pass therebetween into the return duct 77. To assure the same, the 30 wall 68c is suitably corrugated to provide an expanded section adjacent the gates 70a, wherein the velocity of the air current is diminished so that an air pocket will be formed thereat. This air pocket will enhance the movement of the stem 35 portions having adhering laminae into the gap between the gates 70a. As a further safeguard against the delivery of stem portions to the tower outlet, the wall 68c is so corrugated as to provide an expanded section of even greater cross- 40 section adjacent the outlet of the secondary channel, thereby further reducing the velocity of the air current therethrough and enhancing the separation of the laminae from the stem portions. The gate 70 underlies a reentrant 45 portion on the bottom of the lip 68f formed on the upper end of the wall 68c and may be set by the attendant to permit the delivery of laminae only to the tower outlet. Any stem portions substantially devoid of laminae, which may 50 have been carried up into the secondary channel, will impinge on the walls thereof repeatedly and finally fall down the channel and through the space between upper end of the baffle 68e and the inner wall of the return duct down into the 55 receptacle 76.

The baffles 68d and 68e are adjustably mounted in the side walls of the tower, wherefore they may be set in the most effective positions. Moreover, the inner wall of the duct 77 is depressed 60 adjacent the baffle 68e to provide a gap there-between sufficiently large to permit the stem portions to drop freely therethrough. It should also be noted that the top of the tower 11 is cut away at the juncture of the tower inlet and outlet, as 65 shown in Fig. 1, and provided with a screen 11b, in order to prevent the building up of back pressure to the blast issuing from the blower nozzle. The same is important because the velocities of 70 separate air currents are just sufficient to carry 75

the laminae into the tower outlet, in order that they may settle under their own weight into the receptacle 69 and thereby avoid the scattering of laminae which would take place if an air current of any appreciable velocity were directed into the receptacle. Under these conditions it will be apparent that even a slight building of back pressure would disturb the equilibrium requisite for proper operation.

10 The stem portions having adhering laminae, which pass over into the return duct 71, are trapped therein and fall down on to a return conveyor belt which carries them to a chute 79 suspended over the feed belt 14. These laminae 15 then fall on to the belt 14 and pass through the machine a second time for further removal of laminae from the stem portions and further winnowing thereof. The return conveyor belt 78 is driven by means of a pulley 18a (Fig. 1) and 20 trained over an idler pulley 18b. The entire conveyor belt 78 is enclosed within a housing 18c attached to the tower 11 and the main frame 10. The driving pulley 18a is mounted on a shaft 78d supported in a bearing of housing 18c 25 and a bearing bracket 78e attached to the threshing chamber casting 13a. Shaft 78d carries a gear 18f meshing with a gear 18g loosely mounted on a stud 18h set in the bracket 78e. To gear 18g is attached a sprocket 18i (Fig. 3) which, 30 through a chain 18k, is continuously driven by a sprocket 18l mounted on the feed conveyor drive shaft 30.

The twin blower 67 (Figs. 1, 6 and 7) is of a novel construction and consists of two blower 35 housings 67a (Fig. 7), each housing enclosing a centrifugal fan of well known construction driven by means of a shaft 80 supported in bearings 81 of bearing brackets 82 held by a pair of cross-bars 83 supported by the main frame 10. 40 Cross-bars 83 also support the two blower housings 67a, the latter being provided with lugs 84 secured to the former (Fig. 6). Shaft 80 also carries a pulley 85 which may be driven by any suitable means such as a pair of V-belts 86 from a 45 pulley 87 (Figs. 1 and 3) mounted on the drum shaft 19. The outlets of the two blower housings 67a are provided with a common nozzle 66 whereby the air currents created by each blower fan are united. A partition 88 (Fig. 6) located at 50 the mouth of nozzle 66 directs some of the air current out of one orifice 65 while the rest of the air blast is guided out of the other orifice 75 of the nozzle. The nozzle 66 is so disposed that its orifice 65 is located under the channel between the partitions 68 and 68b of tower 11 and its 55 other orifice 75 delivers the second blast into the channel between the partition 68c and the return duct 71. The separating action achieved by the described arrangement of the tower and 60 nozzle actually does the work of two machines and assures clean scrap filler.

In order to be able to regulate or balance the air currents directed out of orifices 65 and 75, an adjustable wedge-shaped deflector 89 is provided 65 and can be set to obtain any desirable flow of air through the two orifices 65 and 75. The deflector 89 is fulcrumed on hubs 90 (Figs. 6 and 7) attached to the interior of the side walls of nozzle 66. The central portion of deflector 89 70 carries a pair of operating bars 91, the hooked ends of which extend through slots 92 (Fig. 6) in nozzle walls 66 to the outside of the same. These projecting ends of bars 91 are provided with notches 93 which receive the studs 94 of a 75 collar 95 mounted on a threaded shaft 96 sup-

ported in bearing brackets 97 fastened to the outside of the nozzle walls 66. One end of shaft 96 is equipped with a knob 98 by means of which shaft 96 can be turned, causing collar 95 to move up or down therealong and operate the bars 91 to change the position of the deflector 89 and thereby effect an increase or a decrease of the air flow through the orifice 65 or 75. In this manner the velocity of the primary air blast may be varied with respect to the secondary air blast. 10 In order to completely control the amount of air taken in through the inlets 99 in each side of the blower housings 67a, each inlet 99 is equipped with a shutter 100. To each shutter 100 is fastened a supporting lug 101, and each pair of 15 shutters controlling one housing is mounted on an individual shaft 102, thus enabling operation of the shutter control for one housing independently of the other. Each shaft 102 is supported in bearings of the main frame 10 and bearing 20 brackets 103 supported by a cross member 104 of main frame 10. To one end of each shaft 102 is fastened an operating arm 105 to which is pivoted a threaded lug 106 engaging with a threaded operating shaft 107 supported by a stud 108 pivoted to the main frame 10. The uppermost portion of each shaft 107 is equipped with a knob 109 by means of which the shafts 107 can be turned in either direction, thereby causing the shutters 100 to open or close the inlets 99 of the 30 respective housing 67a. This arrangement enables the operator to control the velocity of both air blasts and set the shutters for a light, medium or strong air current as required to obtain best possible results in the separating and clean- 35 ing of the different grades of tobacco.

A modified form of nozzle control shown in Fig. 8 can be used for regulating the amount of air current directed through each orifice 65 and 40 75 of nozzle 66. In this type of control the orifices 65 and 75 are provided with sets of shutters 110 mounted on shafts 111 pivoted in the side walls of the nozzle 66. The shutters 110 of each set are connected to each other by a link 112, and one shaft 111 of each set is equipped with a 45 knob 113 by means of which each set of shutters 110 can be positioned at any desirable angle, so that any desirable flow of air can be obtained from each of the two inlets 65 and 75. Each knob 113 also carries a pointer 114 for the purpose of 50 indicating the position of the shutters 110 to the operator. In this type of control the mouth of the nozzle is similarly divided by a stationary streamlined partition 115 into two orifices 65 and 75. 55

Instead of using the conveyor screen belt 47 shown in Fig. 1, the same may also be replaced by a suitable conveyor belt of imperforate material, such as leather, canvas, etc.; and the suction intake 48, the suction fan 49, the suction 60 conduit 53 and the suction chamber 54 are eliminated, wherefore the separating tower 11a is suitably modified as illustrated in Fig. 5 to remove the dust from the disintegrated tobacco leaves while the same are being winnowed. In 65 this construction the top and one end wall of the tower are partly cut away and replaced by a screen 116 which is covered by a jacket 117 provided with a conduit 118 connected to a housing 49a enclosing a suction fan carrying a pulley 70 50 driven by a belt 51 from the pulley 52 on motor shaft 23. The construction of the winnowing tower and the twin blower is otherwise the same as that shown in Fig. 1, and the air currents created by the twin blower 67 blow all dust and 75

sand upward to the screen 116 through which it is drawn by the suction created by fan 49a. This suction also acts to remove the dust from the jacket 117 and deliver the same through the outlet of the fan housing into a suitable receptacle (not shown). In order to prevent any back pressure in the tower 11a the top of the jacket 117 is provided with an adjustable relief valve 119 (Fig. 5).

10 Moreover, the belt 47 may be eliminated together with the suction intake, fan, housing and chamber; and the tower may be arranged close to the threshing chamber together with the blower 67 to cause the latter to blow the leaf fragments 15 falling through the apertures of the concave directly into the tower for the winnowing thereof in the manner just described.

What is claimed is:

1. In a tobacco stemming and disintegrating 20 machine, the combination with disintegrating means operating to break up tobacco leaves into fragments and remove laminae from the same, of a device for winnowing the disintegrated tobacco to segregate therefrom in three separate 25 portions the laminae, the stem fragments having adhering laminae and the stem fragments substantially devoid of laminae, and returning the stem fragments having adhering laminae to said disintegrating means for further removal of the 30 laminae from the same, and means for delivering the disintegrated tobacco to said device.

2. In a tobacco stemming and disintegrating 35 machine, the combination with disintegrating means operating to break up tobacco leaves into fragments and remove laminae from the same, of a device for winnowing the disintegrated tobacco to segregate therefrom the laminae and any stem portions substantially devoid of laminae and returning the stem portions having adhering laminae to said disintegrating means for further removal of the laminae from the same, and means for delivering the disintegrated tobacco to said device, said device also acting to trap curled tip ends and return them to said 45 means.

3. In a tobacco stemming and disintegrating 50 machine, the combination with disintegrating means operating to break up tobacco leaves into fragments and remove laminae from the same, of a device for winnowing the disintegrated tobacco to segregate therefrom in three separate portions the laminae, the stem fragments having adhering laminae and the stem fragments substantially devoid of laminae, and returning 55 the stem fragments having adhering laminae to said disintegrating means for further removal of the laminae from the same, and means for delivering the disintegrated tobacco to said device, said device also acting to remove dust and sand 60 from the disintegrated tobacco while it is being winnowed.

4. In a tobacco stemming and disintegrating 65 machine, the combination with disintegrating means operating to break up tobacco leaves into fragments and remove laminae from the same, of a device for winnowing the disintegrated tobacco to segregate therefrom in three separate portions the laminae, the stem fragments having adhering laminae and the stem fragments substantially devoid of laminae, and returning 70 the stem fragments having adhering laminae to said disintegrating means for further removal of the laminae from the stem portions, and means for delivering the disintegrated tobacco to said device, and including a winnowing tower wherein 75

the disintegrated tobacco is winnowed having a perforated wall, a screen covering the perforation in said wall, a jacket covering said screen, and a suction fan connected to said jacket to create suction therein and thereby remove dust 5 from said tower through the interstices of said screen.

5. In a tobacco stemming and disintegrating machine, the combination with disintegrating means operating to break up tobacco leaves into 10 fragments and remove laminae from the same, of a device for winnowing the disintegrated tobacco to segregate therefrom the laminae and stem portions which are substantially devoid of laminae and returning any stem portions having 15 adhering laminae to said disintegrating means for further removal of the laminae from the stem portions, and a conveyor for delivering the disintegrated tobacco to said device.

6. In a tobacco stemming and disintegrating 20 machine, the combination with disintegrating means operating to break up tobacco leaves into fragments and remove laminae from the same, of a device for winnowing the disintegrated tobacco to segregate therefrom the laminae and 25 stem portions which are substantially devoid of laminae and returning any stem portions having adhering laminae to said disintegrating means for further removal of the laminae from the stem portions, a conveyor for delivering the disintegrated tobacco to said device, and mechanism for removing dust and sand from the disintegrated tobacco while it is being transported by said conveyor.

7. In a tobacco stemming and disintegrating 35 machine, the combination with disintegrating means operating to break up tobacco leaves into fragments and remove laminae from the same, of a device for winnowing the disintegrated tobacco to segregate therefrom the laminae and 40 any stem portions substantially devoid of laminae and returning the stem portions having adhering laminae to said disintegrating means for further removal of the laminae from the stem portions, means for delivering the disintegrated 45 tobacco to said device, and a conveyor for delivering the disintegrated tobacco to said device, said device including means for subjecting the disintegrated tobacco delivered by said conveyor to a primary current of air for segregation of 50 most of the laminae therefrom and resubjecting the remainder to a secondary current of air for segregation of the remaining laminae therefrom.

8. In a tobacco stemming and threshing machine, the combination with a thresher, of means 55 for delivering tobacco leaves to said thresher in order to break up the leaves into fragments and remove laminae from the same, and a device for winnowing the disintegrated tobacco to segregate therefrom in three separate portions the laminae, the stem fragments having adhering laminae and the stem fragments which are substantially devoid of laminae, and a conveyor for transporting the disintegrated tobacco from said thresher to said device.

9. In a tobacco stemming and threshing machine, the combination with a thresher, of means for delivering tobacco leaves to said thresher in order to break up the leaves into fragments and remove laminae from the same, a device for winnowing the disintegrated tobacco to segregate 70 therefrom the laminae and the stem portions which are substantially devoid of laminae, a conveyor for transporting the disintegrated tobacco from said thresher to said device, and mechanism 75

for removing dust and sand from the tobacco leaves in said means and the disintegrated tobacco while it is being transported by said conveyor.

5 10. The combination with disintegrating means operating to break up tobacco leaves into fragments and remove laminae from the same, of a device for winnowing the disintegrated tobacco leaves to segregate in three separate portions the 10 laminae, any stem fragments substantially devoid of laminae and the stem fragments having adhering laminae, and means for delivering the disintegrated tobacco leaves to said device.

11. The combination with disintegrating means 15 operating to break up tobacco leaves into fragments and remove laminae from the same, of a device for winnowing the disintegrated tobacco leaves to segregate in separate portions the laminae, and the stem fragments having adhering laminae, said device operating to segregate 20 with the stem fragments having adhering laminae any curled tip ends present in the disintegrated leaves.

12. The combination with disintegrating means 25 operating to break up tobacco leaves into fragments and remove laminae from the same, of a device for winnowing the disintegrated tobacco leaves to segregate therefrom the stem fragments having adhering laminae, said device 30 operating to segregate with the stem fragments having adhering laminae any curled tip ends present in the disintegrated leaves and return the same to said disintegrating means.

13. The combination with disintegrating means 35 operating to break up tobacco leaves into fragments and remove laminae from the same, of a device for winnowing the disintegrated tobacco leaves to segregate in three separate portions the laminae, any stem portions substantially devoid 40 of laminae and the stem portions having adhering laminae.

14. The combination with disintegrating means operating to break up tobacco leaves into fragments and remove laminae from the same, of a 45 device for winnowing the disintegrated tobacco leaves to segregate the laminae, any stem portions substantially devoid of laminae and the stem portions having adhering laminae, a conveyor for delivering the disintegrated leaves to 50 said device, and mechanism for removing dust and sand from the disintegrated leaves being transported by said conveyor.

15. The combination with disintegrating means 55 operating to break up tobacco leaves into fragments and remove laminae from the same, of a device for winnowing the disintegrated leaves to segregate the laminae, any stem portions substantially devoid of laminae and the stem portions having adhering laminae, a traveling end- 60 less screen belt arranged to receive on its upper run the disintegrated leaves from said means, mechanism for agitating said upper run to loosen the dust and sand present in the disintegrated leaves, and suction means for removing the 65 loosened sand and grit through the interstices of said screen belt.

16. The combination with disintegrating means 70 operating to break up tobacco leaves into fragments and remove laminae from the same, of a device for winnowing the disintegrated tobacco leaves to segregate the laminae, any stem portions substantially devoid of laminae and the stem portions having adhering laminae, means for delivering the disintegrated tobacco leaves 75 to said device, said device also acting to remove

dust and sand from the disintegrated leaves while they are being winnowed.

17. The combination with disintegrating means operating to break up tobacco leaves into fragments and remove laminae from the same, of a device for winnowing the disintegrated tobacco leaves to segregate the laminae, any stem portions substantially devoid of laminae and the stem portions having adhering laminae, means for delivering the disintegrated tobacco leaves 10 to said device, said device also acting to remove dust and sand from the disintegrated leaves while they are being winnowed, and including a tower wherein the disintegrated leaves are winnowed, said tower having a perforated wall, a screen 15 covering said perforation, a jacket covering said screen, and a suction fan connected to said jacket to create suction therein and thereby remove dust from the tower through the interstices of said screen.

18. The combination with disintegrating means operating to break up tobacco leaves into fragments and remove laminae from the same, of a device for winnowing the disintegrated tobacco leaves to segregate in three separate portions the 20 laminae, any stem portions substantially devoid of laminae and the stem portions having adhering laminae, said device including a tower having an intercommunicating inlet and outlet, a blower delivering a blast of air to said inlet to 25 winnow laminae from the disintegrated leaves therein and carry the laminae into the tower outlet, said tower being perforated at the juncture of said inlet and outlet to vent the air blast delivered to said inlet and thereby prevent building 30 up of back pressure therein, and a screen covering said perforation.

19. The combination with disintegrating means operating to break up tobacco leaves into fragments and remove laminae from the same, of a 40 device for winnowing the disintegrated tobacco leaves to segregate in three separate portions the laminae, any stem fragments substantially devoid of laminae and the stem fragments having adhering laminae, said device including means for 45 subjecting the disintegrated leaves delivered by said means to a primary current of air for winnowing of most of the laminae therefrom and re-subjecting the remainder to a separate secondary current of air for winnowing of the remaining laminae therefrom.

20. The combination with means for disintegrating tobacco leaves to substantially uniform pieces, of a device for winnowing the disintegrated tobacco leaves to segregate in three separate portions the laminae, any stem fragments substantially devoid of laminae and the stem fragments having adhering laminae, and means arranged to receive the uniform pieces from the disintegrating means and convey them to said 60 device.

21. The combination with means for disintegrating tobacco leaves, of a device for winnowing the disintegrated tobacco leaves to segregate therefrom as a separate portion the stem fragments having adhering laminae, said device operating to return the stem fragments having adhering laminae to said disintegrating means for further removal of laminae therefrom.

22. The combination with means for disintegrating tobacco leaves, of a device for winnowing the disintegrated tobacco leaves to segregate therefrom as a separate portion the stem fragments having adhering laminae, said device operating to segregate with the stem fragments hav- 75

ing adhering laminae any curled tip ends present in the disintegrated leaves and return the same to said disintegrating means for further disintegration.

23. The combination with a tower having an inlet and outlet, said inlet being subdivided into primary and secondary feed channels communicating with said outlet, of means for creating separate currents of air through the primary and secondary feed channels, and means for delivering disintegrated leaves to said primary channel whereby any free laminae present in the disintegrated leaves will be carried up the primary channel and into the tower outlet, said inlet being also provided with a return channel communicating with said primary and secondary channels and arranged to conduct into the air current through the secondary channel the stem portions carried over into the return channel from the primary channel, for further winnowing therefrom of any laminae carried over therewith.

24. The combination with a tower having an inlet and outlet, said inlet being subdivided into primary and secondary feed channels communicating with said outlet, of means for creating separate currents of air through the primary and secondary feed channels, means for delivering disintegrated leaves to said primary channel whereby any free laminae present in the disintegrated leaves will be carried up the primary channel and into the tower outlet, said inlet being also provided with a return channel communicating with said primary and secondary channels and arranged to conduct into the air current through the secondary channel the stem portions carried over into the return channel from the primary channel, for further winnowing therefrom of any laminae carried over therewith, said secondary channel being provided with a pocket through which any stem portions having adhering laminae may be propelled by the air current through the secondary channel.

25. The combination with a tower having an inlet and an outlet, said inlet being subdivided into primary and secondary feed channels communicating with said outlet, of means for creating separate air currents through the primary and secondary channels, and means for delivering disintegrated tobacco leaves to said primary channel whereby any free laminae present in the disintegrated leaves will be carried up the primary channel and into the tower outlet, said inlet being also provided with a return channel communicating with said primary and secondary channels and arranged to conduct into the air current through the secondary channel any stem portions and curled tip ends carried into the return channel from the primary channel, for further winnowing therefrom of any laminae carried over therewith.

26. The combination with a tower having an inlet and an outlet, said inlet being subdivided into primary and secondary feed channels communicating with said outlet, of means for creating separate air currents through the primary and secondary channels, and means for delivering disintegrated tobacco leaves to said primary channel whereby any free laminae present in the disintegrated leaves will be carried up the primary channel and into the tower outlet, said inlet being also provided with a return channel communicating with said primary and secondary channels and arranged to conduct into the air current through the secondary channel any stem portions and curled tip ends carried into the re-

turn channel from the primary channel, for further winnowing therefrom of any laminae carried over therewith, said secondary channel being provided with a pocket through which the curled tip ends and any stem portions having adhering laminae may be carried by the air current through the secondary channel.

27. The combination with a tower having an inlet and an outlet, said inlet being subdivided into primary and secondary feed channels communicating with said outlet, of means for creating separate air currents through the primary and secondary channels, and means for delivering disintegrated tobacco leaves to said primary channel whereby any free laminae present in the disintegrated leaves will be carried up the primary channel and into the tower outlet, said inlet being also provided with a return channel communicating with said primary and secondary channels and arranged to conduct into the air current through the secondary channel any stem portions and curled tip ends carried into the return channel from the primary channel, for further winnowing therefrom of any laminae carried over therewith, said primary channel having an expanded section adjacent the juncture of the return channel therewith to reduce the velocity of the air current through the expanded section and thereby permit the stem portions and curled tip ends to be carried over into the return channel.

28. The combination with a tower having an inlet and outlet, said inlet being subdivided into primary and secondary feed channels communicating with said outlet, of means for creating separate currents of air through the primary and secondary feed channels, and means for delivering disintegrated leaves to said primary channel whereby any free laminae present in the disintegrated leaves will be carried up the primary channel and into the tower outlet, said inlet being also provided with a return channel communicating with said primary and secondary channels and arranged to conduct into the air current through the secondary channel the stem portions carried over into the return channel from the primary channel, for further winnowing therefrom of any laminae carried over therewith, said primary channel having a tortuous configuration whereby the impinging of the stem portions on the walls thereof will enhance their delivery to the return channel.

29. The combination with a winnowing tower having an intercommunicating inlet and outlet, of means for delivering disintegrated tobacco to the inlet of said tower, and a blower for delivering a blast of air to the tower inlet to winnow free laminae from the disintegrated leaves and carry the same into the tower outlet, said tower being perforated at the juncture of said inlet and outlet to prevent the building up in the tower of back pressure to the blast delivered from said blower, and said perforation being provided with a screen.

30. The combination with a tower having an inlet and an outlet, said inlet being subdivided into primary and secondary feed channels communicating with said outlet, of a blower delivering a divided blast for creating separate air currents through the primary and secondary channels, and means for delivering disintegrated leaves to said primary channel whereby any free laminae present in the disintegrated leaves will be carried up the primary channel and into the tower outlet, said inlet being also provided with a return channel communicating with said primary

- and secondary channels and arranged to conduct into the air current through the secondary channel any stem portions carried into the return channel from the primary channel for further winnowing of any laminae which may be carried over with the stem portions.
31. The combination with a tower having an inlet and an outlet, said inlet being subdivided into primary and secondary feed channels communicating with said outlet, of a blower delivering a divided blast for creating separate air currents through the primary and secondary channels, and means for delivering disintegrated leaves to said primary channel whereby any free laminae present in the disintegrated leaves will be carried up the primary channel and into the tower outlet, said inlet being also provided with a return channel communicating with said primary and secondary channels and arranged to conduct into the air current through the secondary channel any stem portions carried into the return channel from the primary channel for further winnowing of any laminae which may be carried over with the stem portions, said blower being provided with a nozzle having a pair of orifices and an adjustable deflector arranged between said orifices to vary the flow of air through the orifices into said feed channels.
32. The combination with a tower having an inlet and an outlet, said inlet being subdivided into primary and secondary feed channels communicating with said outlet, of a blower delivering a divided blast for creating separate air currents through the primary and secondary channels, and means for delivering disintegrated leaves to said primary channel whereby any free laminae present in the disintegrated leaves will be carried up the primary channel and into the tower outlet, said inlet being also provided with a return channel communicating with said primary and secondary channels and arranged to conduct into the air current through the secondary channel any stem portions carried into the return channel from the primary channel for further winnowing of any laminae which may be carried over with the stem portions, said blower including a pair of blower housings each having an inlet, fans in each of said housings, a nozzle communicating with both of said housings and provided with a pair of orifices, shutters for each of said blower housing inlets, and means for independently opening and closing each of said shutters to control the flow of air through either orifice.
33. The combination with a tower having an inlet and an outlet, said inlet being subdivided into primary and secondary feed channels communicating with said outlet, of a blower delivering a divided blast for creating separate air currents through the primary and secondary channels, and means for delivering disintegrated leaves to said primary channel whereby any free laminae present in the disintegrated leaves will be carried up the primary channel and into the tower outlet, said inlet being also provided with a return channel communicating with said primary and secondary channels and arranged to conduct into the air current through the secondary channel any stem portions carried into the return channel from the primary channel for further winnowing of any laminae which may be carried over with the stem portions, said blower including a nozzle having a pair of orifices, sets of shutters arranged in each orifice, and mechanism for independently adjusting the set of shutters in each orifice to govern the flow of air therethrough.
34. The combination with a tower having an inlet and an outlet, said inlet being subdivided into primary and secondary feed channels communicating with said outlet, of a blower delivering a divided blast for creating separate air currents through the primary and secondary channels, and means for delivering disintegrated leaves to said primary channel whereby any free laminae present in the disintegrated leaves will be carried up the primary channel and into the tower outlet, said inlet being also provided with a return channel communicating with said primary and secondary channels and arranged to conduct into the air current through the secondary channel any stem portions carried into the return channel from the primary channel for further winnowing of any laminae which may be carried over with the stem portions, the juncture of said secondary channel with the tower outlet and the juncture of the return channel with the primary channel being provided with adjustable gates which may be set so that the laminae may be winnowed from various grades of disintegrated tobacco.
35. The combination with a tower having an inlet and an outlet, said inlet being subdivided into primary and secondary feed channels communicating with said outlet, of a blower delivering a divided blast for creating separate air currents through the primary and secondary channels, and means for delivering disintegrated leaves to said primary channel whereby any free laminae present in the disintegrated leaves will be carried up the primary channel and into the tower outlet, said inlet being also provided with a return channel communicating with said primary and secondary channels and arranged to conduct into the air current through the secondary channel any stem portions carried into the return channel from the primary channel for further winnowing of any laminae which may be carried over with the stem portions, said secondary channel being provided with a pocket through which any stem portions having adhering laminae may be carried, said pocket having relatively adjustable gates.
36. The combination with a winnowing tower having an inlet and an outlet, said inlet being subdivided by a central wall into upwardly extending primary and secondary feed channels communicating with said outlet, and said inlet being provided with partitions forming return channels extending upwardly in said primary channel, a baffle-plate arranged at the entrance of said secondary channel, a blower for delivering separate currents of air to said primary and secondary channels, and means for delivering disintegrated leaves to said primary channel whereby the free laminae present in the disintegrated leaves will be carried up the primary channel and into the tower outlet and any stem portions carried over into the return channels will drop down therethrough into the air current through the secondary channel for further winnowing of any laminae which may be carried over with the stem portions.
37. The combination with a winnowing tower having an inlet and an outlet, said inlet being subdivided by a central wall into upwardly extending primary and secondary feed channels communicating with said outlet, and said inlet being provided with partitions forming return channels extending upwardly in said primary channel.

channel, a baffle-plate arranged at the entrance of said secondary channel, a blower for delivering separate currents of air to said primary and secondary channels, and means for delivering disintegrated leaves to said primary channel whereby the free laminae present in the disintegrated leaves will be carried up the primary channel and into the tower outlet and any stem portions carried over into the return channels will drop down therethrough into the air current through the secondary channel for further winnowing of any laminae which may be carried over with the stem portions, the lower ends of said partitions being provided with streamlined lips adjacent said baffle-plate to reduce the resistance to the flow of the air current into the secondary channel and prevent the formation of whirlpools therein.

38. The combination with means for disintegrating tobacco leaves, of mechanism for conveying the leaves disintegrated by said means and simultaneously separating dust and sand therefrom, said mechanism including a traveling endless belt underlying said means to receive the disintegrated leaves therefrom and convey them away, said belt being provided with apertures fine enough to permit the passage of dust and sand therethrough and yet retain stem portions and laminae, means for agitating the portion of said belt on which the leaves are being conveyed to loosen the dust and sand therein, a suction intake located below said belt, and a suction fan for creating suction in said intake and thereby removing the dust and sand through the apertures of said belt.

39. The combination with a winnowing tower having an inlet and outlet, said inlet being subdivided into primary and secondary feed channels communicating with said outlet and intermediate channels communicating with said primary and secondary channels, of a device for creating separate air currents through said primary and secondary channels whereby the free laminae present in disintegrated tobacco leaves introduced into said primary channel will be carried up the primary channel and into the tower outlet, said primary channel being provided with an expanded portion adjacent the juncture of the return channel therewith to decrease the velocity of the air current through the expanded portion and permit stem portions to be carried over into the return channel and conducted into the air current through the secondary channel for further winnowing of any laminae carried over with the stem portions.

40. The combination with a winnowing tower having an inlet and outlet, said inlet being subdivided into primary and secondary feed channels communicating with said outlet and intermediate channels communicating with said primary and secondary channels, of a device for creating separate air currents through said primary and secondary channels whereby the free laminae present in disintegrated tobacco leaves introduced into said primary channel will be carried up the primary channel and into the tower outlet, said primary channel being provided with an expanded portion adjacent the juncture of the return channel therewith to decrease the velocity of the air current through the expanded portion and permit stem portions to be carried over into the return channel and conducted into the air current through the secondary channel for further winnowing of any laminae carried over with the stem portions, said secondary channel being also provided with a pocket and an expanded section

adjacent said pocket to reduce the velocity of the secondary air current through the expanded section of the secondary channel and permit any stem portions having adhering laminae to be carried over into said pocket.

41. The combination with a winnowing tower having an inlet and outlet, said inlet being subdivided into upwardly extending primary and secondary feed channels communicating with said outlet and intermediate return channels extending upwardly to different levels in said primary channel, of a device for creating separate currents of air upwardly through said primary and secondary channels, whereby the free laminae present in disintegrated leaves introduced into said primary channel will be carried up the primary channel and into the tower outlet, the primary channel being provided with expanded portions adjacent the upper ends of the return channels to reduce the velocity of the air current in the expanded sections and permit the stem portions to be carried over into the return channel and fall down therethrough into the air current through the secondary channel for further winnowing of any laminae carried over with the stem portions.

42. The combination with a tower having an inlet and outlet, said inlet being subdivided into primary and secondary feed channels communicating with said outlet, of means for creating separate air currents through the primary and secondary channels, whereby any free laminae present in disintegrated tobacco leaves introduced into said primary channel will be carried up the primary channel and into the tower outlet, said inlet being also provided with a return channel communicating with said primary and secondary channels and arranged to conduct into the air current through the secondary channel the stem portions carried over into the return channel from the primary channel, for further winnowing therefrom of any laminae carried over therewith.

43. The combination with a tower having an inlet and outlet, said inlet being subdivided into primary and secondary feed channels communicating with said outlet, of means for creating separate air currents through the primary and secondary channels, whereby any free laminae present in disintegrated tobacco leaves introduced into said primary channel will be carried up the primary channel and into the tower outlet, said inlet being also provided with a return channel communicating with said primary and secondary channels and arranged to conduct into the air current through the secondary channel the stem portions carried over into the return channel from the primary channel, for further winnowing therefrom of any laminae carried over therewith, said secondary channel being provided with a pocket through which any stem portions having adhering laminae may be propelled by the air current through the secondary channel.

44. The combination with a tower having an inlet and an outlet, said inlet being subdivided into primary and secondary feed channels communicating with said outlet, of means for creating separate air currents through the primary and secondary channels whereby any free laminae present in disintegrated tobacco leaves introduced into the primary channel will be carried up the primary channel and into the tower outlet, said inlet being also provided with a return channel communicating with said primary and secondary channels and arranged to conduct into the air

current through the secondary channel any stem portions and curled tip ends carried into the return channel from the primary channel, for further winnowing therefrom of any laminae carried over therewith.

45. The combination with a tower having an inlet and an outlet, said inlet being subdivided into primary and secondary feed channels communicating with said outlet, of means for creating 10 separate air currents through the primary and secondary channels whereby any free laminae present in disintegrated tobacco leaves introduced into the primary channel will be carried up the primary channel and into the tower outlet, said 15 inlet being also provided with a return channel communicating with said primary and secondary channels and arranged to conduct into the air current through the secondary channel any stem portions and curled tip ends carried into the return channel from the primary channel, for further winnowing therefrom of any laminae carried over therewith, said secondary channel being provided with a pocket through which the curled tip ends and stem portions having adhering laminae may be carried by the air current through 20 the secondary channel.

46. The combination with a tower having an inlet and an outlet, said inlet being subdivided into primary and secondary feed channels communicating with said outlet, of means for creating 30 separate air currents through the primary and secondary channels whereby any free laminae present in disintegrated tobacco leaves introduced into the primary channel will be carried up the primary channel and into the tower outlet, said 35 inlet being also provided with a return channel communicating with said primary and secondary channels and arranged to conduct into the air current through the secondary channel any stem portions and curled tip ends carried into the return channel from the primary channel, for further winnowing therefrom of any laminae carried over therewith, said primary channel having an expanded section adjacent the juncture of the 40 return channel therewith to reduce the velocity of the air current through the expanded section and thereby permit the stem portions and curled tip ends to be carried over into the return channel.

47. The combination with a tower having an inlet and outlet, said inlet being subdivided into primary and secondary feed channels communicating with said outlet, of means for creating 50 separate air currents through the primary and secondary channels, whereby any free laminae present in disintegrated tobacco leaves introduced into said primary channel will be carried up the primary channel and into the tower outlet, said inlet being also provided with a return channel 55 communicating with said primary and secondary channels and arranged to conduct into the air current through the secondary channel the stem portions carried over into the return channel from the primary channel, for further winnowing therefrom of any laminae carried over therewith, said primary channel having a tortuous configuration whereby the impinging of the stem portions on the walls thereof will enhance their delivery to the return channel.

48. The combination with a tower having an inlet and outlet, said inlet being subdivided into primary and secondary feed channels communicating with said outlet, of a blower for creating 60 separate air currents through the primary and secondary channels whereby any free laminae

present in disintegrated tobacco leaves introduced into said primary channel will be carried up the same and into the tower outlet, said inlet being also provided with a return channel communicating with said primary and secondary channels and arranged to conduct into the air current through the secondary channel any stem portions carried into the return channel from the primary channel for further winnowing of laminae which may be carried over with the stem portions.

49. The combination with a tower having an inlet and outlet, said inlet being subdivided into primary and secondary feed channels communicating with said outlet, of a blower for creating 10 separate air currents through the primary and secondary channels whereby any free laminae present in disintegrated tobacco leaves introduced into said primary channel will be carried up the same and into the tower outlet, said inlet being also provided with a return channel communicating 15 with said primary and secondary channels and arranged to conduct into the air current through the secondary channel any stem portions carried into the return channel from the primary channel for further winnowing of laminae which may be 20 carried over with the stem portions, said blower being provided with a nozzle having a pair of orifices and an adjustable deflector arranged between said orifices to vary the flow of air through 25 said orifices into said feed channels.

50. The combination with a tower having an inlet and outlet, said inlet being subdivided into primary and secondary feed channels communicating with said outlet, of a blower for creating 30 separate air currents through the primary and secondary channels whereby any free laminae present in disintegrated tobacco leaves introduced into said primary channel will be carried up the same and into the tower outlet, said inlet being also provided with a return channel communicating 35 with said primary and secondary channels and arranged to conduct into the air current through the secondary channel any stem portions carried into the return channel from the primary channel for further winnowing of laminae which may be carried over with the stem portions, said blower including a pair of blower 40 housings each having an inlet, fans in each of said housings, a nozzle communicating with both of said housings and provided with a pair of orifices, shutters for each of said blower housing inlets, and means for independently opening and 45 closing each of said shutters to control the flow of air through either orifice.

51. The combination with a tower having an inlet and outlet, said inlet being subdivided into primary and secondary feed channels communicating with said outlet, of a blower for creating 55 separate air currents through the primary and secondary channels whereby any free laminae present in disintegrated tobacco leaves introduced into said primary channel will be carried up the same and into the tower outlet, said inlet being also provided with a return channel communicating 60 with said primary and secondary channels and arranged to conduct into the air current through the secondary channel any stem portions carried into the return channel from the primary channel for further winnowing of laminae which may be 65 carried over with the stem portions, said blower including a nozzle having a pair of orifices, sets of shutters arranged in each orifice, and mechanism for independently adjusting the set of 70 shutters in each orifice to govern the flow of air therethrough.

52. The combination with a tower having an inlet and outlet, said inlet being subdivided into primary and secondary feed channels communicating with said outlet, of means for creating separate air currents through the primary and secondary channels, whereby any free laminae present in disintegrated tobacco leaves introduced into said primary channel will be carried up the primary channel and into the tower outlet, said inlet being also provided with a return channel communicating with said primary and secondary channels and arranged to conduct into the air current through the secondary channel the stem portions carried over into the return channel from the primary channel, for further winnowing therefrom of any laminae carried over therewith, the juncture of said secondary channel with the tower outlet and the juncture of the return channel with the primary channel being provided with adjustable gates which may be set so that the laminae may be winnowed from various grades of disintegrated tobacco.

53. The combination with a tower having an inlet and outlet, said inlet being subdivided into primary and secondary feed channels communicating with said outlet, of means creating separate air currents through the primary and secondary channels, whereby any free laminae present in disintegrated tobacco leaves introduced into said primary channel will be carried up the primary channel and into the tower outlet, said inlet being also provided with a return channel communicating with said primary and secondary channels and arranged to conduct into the air current through the secondary channel the stem portions carried over into the return channel from the primary channel, for further winnowing therefrom of any laminae carried over therewith, said secondary channel being provided with a pocket through which any stem portions having adhering laminae may be carried, said pocket having relatively adjustable gates.

54. The combination with a tower having an inlet and outlet, said inlet being subdivided into primary and secondary feed channels communicating with said outlet, of a blower for creating separate air currents through the primary and secondary channels whereby any free laminae present in disintegrated tobacco leaves introduced into said primary channel will be carried up the same and into the tower outlet, said inlet being also provided with a return channel communicating with said primary and secondary channels and arranged to conduct into the air current through the secondary channel any stem portions carried into the return channel from the primary channel for further winnowing of laminae which may be carried over with the stem portions, said tower being provided with a baffle-plate arranged within the secondary channel to deflect the current of air entering the secondary channel away from one of the walls thereof and being sufficiently spaced from said wall to establish a gap through which stem portions substantially devoid of laminae may drop.

55. The combination with a tower having an inlet and outlet, said inlet being subdivided into primary and secondary feed channels communicating with said outlet, of a blower for creating separate air currents through the primary and secondary channels whereby any free laminae present in disintegrated tobacco leaves introduced into said primary channel will be carried up the same and into the tower outlet, said inlet being also provided with a return channel communi-

cating with said primary and secondary channels and arranged to conduct into the air current through the secondary channel any stem portions carried into the return channel from the primary channel for further winnowing of laminae which may be carried over with the stem portions, and a pair of longitudinally spaced baffle-plates at the entrance of said secondary channel to deflect the secondary current of air away from one of the walls of the secondary channel, the space between said baffle-plates being sufficient to permit stem portions substantially void of laminae to drop therethrough.

56. The combination with a tower having an inlet and outlet, said inlet being subdivided into primary and secondary feed channels communicating with said outlet, of a blower for creating separate air currents through the primary and secondary channels whereby any free laminae present in disintegrated tobacco leaves introduced into said primary channel will be carried up the same and into the tower outlet, said inlet being also provided with a return channel communicating with said primary and secondary channels and arranged to conduct into the air current through the secondary channel any stem portions carried into the return channel from the primary channel for further winnowing of laminae which may be carried over with the stem portions, and a baffle-plate arranged at the entrance of said secondary channel to guide the secondary current of air into said secondary channel, the velocity of the secondary current of air being such that excessively heavy stem portions substantially devoid of laminae may drop therethrough along said baffle-plate.

57. The combination with a tower having an inlet and outlet, said inlet being subdivided into primary and secondary feed channels communicating with said outlet, of a blower for creating separate air currents through the primary and secondary channels whereby any free laminae present in disintegrated tobacco leaves introduced into said primary channel will be carried up the same and into the tower outlet, said inlet being also provided with a return channel communicating with said primary and secondary channels and arranged to conduct into the air current through the secondary channel any stem portions carried into the return channel from the primary channel for further winnowing of laminae which may be carried over with the stem portions, the velocity of the separate air currents being such that foreign matter may drop through both air currents.

58. The combination with a winnowing tower having an inlet and an outlet, said inlet being subdivided by a central wall into upwardly extending primary and secondary feed channels communicating with said outlet, and said inlet being provided with partitions forming return channels extending upwardly in said primary channel, a baffle-plate arranged at the entrance of said secondary channel, and a blower for delivering separate currents of air to said primary and secondary channels whereby any free laminae present in disintegrated tobacco leaves introduced into the primary channel will be carried up the same and into the tower outlet and any stem portions carried over into the return channels will drop down therethrough into the air current through the secondary channel for further winnowing of any laminae which may be carried over with the stem portions.

59. The combination with a winnowing tower

having an inlet and an outlet, said inlet being subdivided by a central wall into upwardly extending primary and secondary feed channels communicating with said outlet, and said inlet being provided with partitions forming return channels extending upwardly in said primary channel, a baffle-plate arranged at the entrance of said secondary channel, and a blower for delivering separate currents of air to said primary and secondary channels whereby any free laminae present in disintegrated tobacco leaves introduced into the primary channel will be carried up the same and into the tower outlet and any stem portions carried over into the return channels will drop down therethrough into the air current through the secondary channel for further winnowing of any laminae which may be carried over with the stem portions, the lower ends of said partitions being provided with streamlined lips adjacent said baffle-plate to reduce the resistance to the flow of the air current into the secondary channel and prevent formation of whirlpools therein.

60. The combination with a winnowing tower having an inlet and an outlet, said inlet being subdivided by a central wall into upwardly extending primary and secondary feed channels communicating with said outlet, and said inlet being provided with partitions forming return channels extending upwardly in said primary channel, a baffle-plate arranged at the entrance of said secondary channel, and a blower for delivering separate currents of air to said primary and secondary channels whereby any free laminae present in disintegrated tobacco leaves introduced into the primary channel will be carried up the same and into the tower outlet and any stem portions carried over into the return channels will drop down therethrough into the air current through the secondary channel for further winnowing of any laminae which may be carried over with the stem portions, the upper end of said wall being provided with a lip having a reentrant portion in its bottom adjacent the juncture of the secondary channel with the tower outlet, and the secondary channel having an adjustable gate below said reentrant portion.

61. In a tobacco threshing machine, the combination with a disintegrator operating to break up tobacco leaves into fragments and free laminae, of a device for winnowing the disintegrated tobacco leaves to segregate the free laminae there-

from, said device including means for creating two separate currents of air whereby the disintegrated tobacco will be initially subjected to one air current to winnow most of the free laminae and stem fragments devoid of laminae therefrom and then re-subjected to the second air current to winnow the remainder of the free laminae therefrom.

62. In a tobacco threshing machine, the combination with a disintegrator operating to break up tobacco leaves into fragments and free laminae, of a device arranged to receive the disintegrated tobacco directly from said disintegrator and winnow the same to segregate laminae therefrom and return the stem fragments having adhering laminae to said disintegrator.

63. In a tobacco threshing machine, the combination with a disintegrator operating to break up tobacco leaves into fragments and free laminae, of a conveyor arranged to deliver tobacco leaves to said disintegrator, and means arranged to receive the disintegrated tobacco directly from said disintegrator and winnow the same to segregate free laminae therefrom and return the stem fragments having laminae to said conveyor.

64. The combination with a winnowing tower having an inlet and an outlet, said inlet being subdivided by a central wall into upwardly extending primary and secondary feed channels communicating with said outlets, and said inlet being provided with partitions forming return channels extending upwardly in said primary channel, a baffle-plate arranged at the entrance of said secondary channel, a blower for delivering separate currents of air to said primary and secondary channels, and means for delivering disintegrated leaves to said primary channel whereby the free laminae present in the disintegrated leaves will be carried up the primary channel and into the tower outlet and any stem portions carried over into the return channels will drop down therethrough into the air current through the secondary channel for further winnowing of any laminae which may be carried over with the stem portions, the upper end of said wall being provided with a lip having a reentrant portion in its bottom adjacent the juncture of the secondary channel with the tower outlet, and the secondary channel having an adjustable gate below said reentrant portion.
